J. G. ROUX, OF CRYSTAL SPRINGS, MISSISSIPPI.

Letters Patent No. 75,579, dated March 17, 1868.

IMPROVED EXTENSION-WARDROBE.

The Schedule referred to in these Letters Patent and making part of the same.

TO ALL WHOM IT MAY CONCERN:

Be it known that I, J. G. Roux, of Crystal Springs, in the county of Copiah, and State of Mississippi, have invented a new and improved Extension-Wardrobe; and I do hereby declare that the following is a full, clear, and exact description thereof, which will enable those skilled in the art to make and use the same, reference being had to the accompanying drawings, forming part of this specification, in which—

Figure 1 is a longitudinal vertical section through the red line X X', fig. 2.

Figure 2 is a longitudinal horizontal section through the red line Z Z', fig. 1.

Figure 3 are the cross-sections through x x', y y', z z', fig. 2.

Similar letters of reference indicate corresponding parts.

This invention consists in so constructing a wardrobe that the two halves of the same, standing vertically, can be separated horizontally by turning a crank on its top, thus exposing uprights, provided with hooks or pegs for hanging clothes upon.

The object is to obtain a wardrobe easy and convenient of access, in which the articles placed in it can be exposed to view and for selection, or closed for security, both operations being performed with facility. It is designed more particularly for merchants, though quite practicable and desirable for household use.

By referring to the drawings, the general parts will be seen to consist of the drums A A', sliding horizontally upon frames B B', the whole supported upon the legs C C' C'. The central post D, which connects the two frames B B', and thus forms a rigid frame, B B', D, is hollow, and contains a vertical shaft, a, which has a step-bearing, c, in the bottom of the lower frame B. This shaft passes through the top frame B', and has its upper bearing in a hollow column, d, which latter is surmounted with arms containing horizontal bearings. The upper end of the shaft a has a bevel-pinion, e, which gears into another bevel-pinion, f, placed on a crank-shaft resting in the horizontal bearings before mentioned, thus forming a bevel-gear for transmitting the motion from the crank g, to which the power is applied.

The drums A A' are elliptical. They constitute the body or wardrobe proper, and may be of any practicable form desired, as round-sided or oblong boxes, or they may be a framework covered with cloth. These drums are provided with heads, E, which have openings or ports at their upper and lower extremities, through which the horizontal frames B B' pass when the wardrobe is closed, and serve as general guides for said drums when in the act of opening or closing. Guide-strips, a', attached to the drums on each side of the frames, bear against the said frames, as indicated in fig. 2, and steady the drums in their sliding motion.

The legs C C are not attached directly to the frame B, as the legs C' C' are, but form a part of a horizontal piece; h' h h' h', which is secured to the frame B at h' h', thus leaving horizontal openings, i i, the use of which will be shortly explained. The under sides of the drums are provided with a slot, shown at j j, which permits the opening and closing of the drums on the said parts h' h', they serving also as a guide to the same. This slot j is not continuous across the whole lower side of the drums, the continuity of the drums being shown at m m, which travel in the openings i i. The recesses for admitting the drums to close completely around the part l, at the bottom, and the shaft-bearing d, at the top, are shown at n n n n.

At the ends of the drums are vertical strips of the same width as the frames B B', and secured to the drums A A' by screws. These strips are shown in section at p p p p, and their office will be hereinafter described. A circular batten, q q q, attached to the drum A', covers the joint of the drums when closed, as shown by the red lines 1 2 3 4 in fig. 2.

Having described the drums, the frame, and some general adjuncts, I will now describe the movement-devices by which the wardrobe is opened and closed.

First, the frames B B' are not solid, but have grooves in them, one for each end, for the passage of the racks r r, figs. 1 and 2, and the cross-sections of the same are shown at x y z in fig. 3. These racks receive their motion from the pinions s s, fig. 1, on the shaft, and are moved inward or outward, according as the crank is rotated. These racks have on their outer ends a step, t, into which are secured projections v v of the aforesaid vertical strip p, so that, when the racks are drawn inward by their pinions, the drums A A' are likewise drawn and brought together, or extended apart, by a reverse motion of the pinions, which motions are imparted by the crank g, as will be seen in fig. 1.

In addition to the opening and closing of the drums, is the movement of the uprights $G G' G''$, which movement is also imparted by the crank indirectly, through a system of devices to be explained. To the upper face of the frame B , and to the lower face of the frame B' , are attached, by screws, wide channels, $c H c$, which contain the sliding feet $u u' u''$ of the uprights $G G' G''$. These are better shown in section at fig. 3. As the operation of any contiguous three of these sliding feet is the same in principle and form, the lower left-hand three only will be specially explained. They are shown in cross-section in fig. 3, the red lines $x x', y y', z z'$, in fig. 2, showing the sections taken.

The channel-bottom H covers the rack-grooves $o o$, and the said channel-bottom is continuous, excepting an opening, k , which extends about half way to the middle of the frame, and is for the purpose of permitting the passage of the projection v , fig. 1, when opening or closing the wardrobe. Elsewhere the floor or bottom of the channel H is unbroken; the uprights having no connection with the racks beneath, except indirectly, through the motion of the drums. Each upright is wide enough to reach across the channel, and a little over; and this part of the invention is better shown by referring to fig. 3, where $G G' G''$ are the uprights, $c c$ the sides of the channel, H the bottom, o the covered groove for the racks, and k the opening in the bottom of the channel, for the purpose previously explained.

The feet of the uprights are short strips of wood, of rectangular section, and their width is one-third of the width of the channel, so that, in lying side by side, they fill up the channel, and slide by each other with easy contact. The outer upright, G , is attached to the feet $u u$, figs. 1, 2, and 3. The position of these feet is between those of the other two uprights, G' and G'' , and fig. 1 shows the longitudinal section of them at $u u$. In fig. 3 this upright is shown attached to the lower foot, at b , section x , and the attachment is made in the middle of the end of the upright, leaving the shoulders $b' b''$ working over the other feet, $u' u''$, on either side. The feet $u u$ of the said upright are provided with a shoulder, s' , at its outer end, for catching against the projections $s'' s''$, on the head of the drum, when the drum is moved outward. The other ends of the same feet are provided with a wide vertical notch, u''' , figs. 1 and 2. In easy contact with this notch is a part of the ends of the second upright G' , which has its feet on the left of the upright, G , as shown in fig. 3, section y . The vertical sides of the notches in the feet of the first upright, G , bear against the ends of the second upright, G' , when the first upright is moved outward or inward, thus carrying with it the second upright. The second upright has no notches in its feet, but there is a stop, p' , in its line of motion, which prevents its undue extension, thus giving stability to the three uprights when they are fully extended, by means of their mutual connection by notches and ends, as hereinbefore shown and described. The third upright, G'' , fig. 3, section z , is provided with feet similarly attached near its edge, opposite to that of G . These feet have notches similar to those of the first upright, into which the end of the second upright, G' , works with easy contact, and for the same objects as those described in the case of the first upright. The three uprights are now connected by means of the notches on the feet of two of them bearing against the ends of the adjacent uprights, and when the wardrobe is opened these uprights separate a certain distance, and when the wardrobe is closed they are drawn together again, thus displaying the contents in the first case, and permitting the closing of the wardrobe in the other, which operations are all accomplished by merely turning the crank. In the act of opening the wardrobe the crank is turned, the rack is thrown outward, carrying with them the drums $A A'$.

The projection s'' , on the drum-heads, catches on the shoulder s' , on the feet of the first upright, G , through which upright acts in its turn upon the other uprights, as shown, and their extension thus follows. In closing, the projection s'' does not perform any function, but the drum-head E bears against the first upright, which, by means of the notches before described, brings the uprights together in a similar manner to that in extending them. The end, s' , of the foot u is drawn in even with the end of the frames $B B'$; by the second upright acting in its notch just as the drums are coming in contact. The uprights are provided with hooks for hanging articles thereon.

The advantages of this invention consist in the facility with which it can be opened and closed, thus serving as a receptacle for fine and frail fabrics, which it is desirable to expose for sale during the day, where they can be inspected with as little handling as possible, and covered completely at night.

I claim as new, and desire to secure by Letters Patent—

1. An extension-wardrobe, constructed substantially as shown and described.
2. The drums or boxes $A A'$, sliding horizontally, substantially as and for the purposes shown and described.
3. The movable uprights $G G' G''$, substantially as and for the purposes shown and described.
4. The frames $B B'$, supported by a post, D , substantially as and for the purposes shown and described.
5. The hollow post D , substantially as and for the purpose shown and described.
6. The vertical shaft a , with its pinions $s s e$, in combination with a wardrobe, substantially as and for the purposes shown and described.
7. The channels H , in combination with the racks $r r$, substantially as and for the purposes shown and described.
8. The uprights $G G' G''$, in combination with the notched feet $u u' u''$, substantially as described, for the purpose specified.
9. Connecting two parts, $A A'$, of a wardrobe with racks $r r$, substantially as and for the purposes shown and described.

J. G. ROUX.
